UNITED STATES PATENT OFFICE

HERBERT ADAMS, OF LIVERPOOL, ENGLAND, ASSIGNOR, BY MESNE ASSIGNMENTS,
TO ASSOCIATED TELEPHONE & TELEGRAPH COMPANY, OF KANSAS CITY, MISSOURI

ROTARY LINE-SWITCH CIRCUIT

Application filed December 6, 1926, Serial No. 152,795, and in Great Britain January 7, 1926. Renewed
May 4, 1929.

This invention relates to telephone systems and is particularly concerned with an improved arrangement for reducing the unguarded interval of a line or switch after it has been taken into use and for ensuring that a line relay will be fully saturated when energized over high resistance junction lines. 55

Where a relay is energized over a high resistance junction line via the back contacts 10 of a relay energized in a local circuit as soon as an idle switch or line is seized, it has been found necessary to delay the operation of the relay energized in a local circuit to ensure full saturation of the relay energized over 15 the junction circuit. This effect has been obtained by placing a small copper slug on the core of the relay in the local circuit, but while this arrangement ensures a satisfactory saturation of the relay in the junction circuit, it also causes the local circuit relay to be 20 slow to operate and slow to release, thereby increasing the unguarded interval of the line which is marked engaged by the local circuit relay due to its slowness to operate, while 25 its increased slowness to release may cause other complications due to other relays restoring first.

According to one feature of the present invention the local circuit relay and junction 30 relay are arranged to jointly extend guarding potential to the release conductor of a selected line before the local circuit relay fully operates to disconnect the junction relay from its energizing circuit. The local 35 circuit relay is rendered quick to operate its contacts which disconnect the junction relay by providing it with an auxiliary winding which is short-circuited jointly by contacts controlled by the junction relay and contacts 40 controlled by its own armature.

In order that the invention may be fully understood and readily carried into effect, an example of the invention will be fully described as applied to hunting switches of a 45 type which select an idle trunk responsive to a calling party removing his receiver.

The single figure of drawing shows by means of the usual circuit diagrams a preferred embodiment of my invention.

50 The drawing shows a hunting switch or

rotary line switch of the type which remains on the contacts last used having a local circuit or switching relay provided with an auxiliary winding connected in a circuit so as to render the relay quick to operate certain contacts slow to operate other contacts and quick to release all its contacts.

Referring now to the drawing, the slow release line relay L is energized over line conductors 2, 3 via the back contacts of armatures 8 and 9 of switching relay K. Relay L upon energizing connects at armature 4, one side of the driving magnet DM and one side of the operating winding of the switching relay K to the private wiper P'; at armature 5 connects earth to the release trunk conductor P and to the other side of the operating winding of the switching relay K, and at armature 6 prepares one point in the circuit for short-circuiting the auxiliary 65 winding of switching relay K. If the wipers of the switch are standing on an idle trunk, switching relay K will immediately energize in series with the driving magnet DM, but if the wipers are resting on a busy line, 70 relay K will be short-circuited and the driving magnet DM will be operated by the earth potential encountered upon the busy line. 75

Assuming that the wipers are standing on an idle line, relay K will immediately energize in series with magnet DM and since its armatures X and X' are arranged to operate before armatures 7, 8 and 9, armature X' will complete the short-circuit for its auxiliary winding and armature X will connect 80 guarding potential to the test wiper P'. Since the operation of armature X' renders the relay K slow in actuating armatures 7, 8 and 9, the energizing circuit of relay L is not broken immediately, and consequently 85 this relay becomes fully saturated before its circuit is opened and as this relay is of the slow-to-release type, it will maintain guarding potential on the release trunk conductor P and on the test wiper P' for an interval 90 longer than that required for the line and release relays of the switch seized by the line switch to operate and feed guarding potential back over the test wiper P'. The 95 operation of armatures 8 and 9 of relay K 100

disconnects relay L, and connects the line conductors 2 and 3 through to the line wipers of the line switch, and the operation of armature 7 prepares a circuit for the meter M. The line switch remains guarded and the relay K energized by guarding potential fed back over wiper P' and controlled by a line relay energized over conductors 2 and 3. Consequently the opening of the circuit 2, 3 10 by the calling party hanging up his receiver will cause guarding potential to be removed from test wiper P', whereupon relay K will immediately de-energize since the circuit of its auxiliary winding is now open at armature 6 by the de-energization of line relay L. In a modification the springs X' of the switching relay K may be arranged as a make-before-break combination and short-circuit the auxiliary winding upon initially 15 energizing, and open the circuit upon fully energizing.

Having now described the nature of my invention and the manner in which it is to be used, what I claim as new is pointed out in 20 the appended claims.

What is claimed is:

1. In a telephone system, a switch including a line relay, a switching relay, means for operating said relays, and means rendered effective after the switching relay has operated to a certain extent to delay the full operation of the switching relay.
2. In a telephone system, a switch including a line relay, a switching relay, means including a winding on the switching relay controlled by contacts on the line relay and short circuited after the switching relay has operated to a certain extent to delay the full operation of the switching relay.
3. In a telephone system, a trunk selecting switch including means for selecting a trunk, a switching relay arranged to operate under predetermined conditions, said switching relay including an operating winding and an additional winding, means for short circuiting said additional winding when the switching relay has operated to a certain extent to reduce the speed of further operation of the switching relay, and contacts on the switching relay closed when the switching relay has operated to its full extent to seize the selected trunk.
4. In a telephone system, a trunk selecting switch having wipers normally resting on the trunk last used, means including a line relay operated when the switch is taken into use to move the wipers off of busy trunks only, means for releasing the line relay when the wipers rest on an idle trunk, said means being delayed in its action thereby insuring a complete energization of said relay prior to its release.
5. In a telephone system, a trunk selecting switch having wipers normally resting on the trunk last used, means including a

line relay operated when the switch is taken into use to move the wipers off of busy trunks, means for releasing the line relay when the wipers rest on an idle trunk, and means controlled by the line relay for rendering said last named means slow in its action, thereby insuring a complete energization of said relay prior to its release.

6. In a telephone system, a trunk selecting switch having wipers normally resting on the trunk last used, means including front contacts of a line relay operated when the switch is taken into use to indicate a busy condition of the switch and to move the wipers off of busy trunks, means for releasing the line relay when the wipers rest on an idle trunk, and means controlled by other front contacts on the line relay for delaying the action of said last named means for a predetermined period of time thereby insuring a complete energization of said line relay prior to its release.

7. In a telephone system, a trunk selecting switch normally associated with a trunk, a line relay operated when the switch is taken into use to indicate a busy condition of the switch, means for associating said switch with other trunks, means for releasing the relay responsive to the association of the switch with a desired trunk, and means controlled by the line relay for delaying the operation of said last named means.

8. In a telephone system, a trunk selecting switch including a line relay, means for operating the line relay when the switch is taken into use, means for releasing the line relay responsive to the switch selecting a desired trunk, and means controlled by the line relay for delaying the operation of said last means.

9. In a telephone system, a trunk selecting switch normally associated with a trunk, a line relay operated when the switch is taken into use to indicate a busy condition of the switch, means for associating said switch with other trunks, means for releasing the relay when the switch is associated with a desired trunk, means for delaying the release operation of the line relay for a period of time dependent upon its degree of energization at the time of its release, and means controlled by the line relay for insuring a complete energization of said line relay at the time of its release.

10. In a telephone system, a trunk selecting switch having wipers normally resting on the trunk last used, means including a line relay operated when the switch is taken into use to indicate a busy condition of the switch and to move the wipers off busy trunks, means for releasing the line relay when the wipers rest on an idle trunk, and means controlled by front contacts on the line relay for rendering said last named means slow acting, to insure a complete en-

ergization of said line relay prior to its release, thereby fixing the time taken for the line relay to release regardless of the busy or idle condition of the trunk upon which the switch wipers rest when the switch is seized.

11. In a trunk selecting switch of the type that when idle is in contact with a trunk, a line relay operated responsive to the seizure 10 of the switch, a switching relay, means controlled by the switching relay for opening the circuit of the line relay, and circuit connections controlled by both relays for insuring the complete energization of the line relay at the time its circuit is opened.

12. In a trunk selecting switch wherein a line relay operates responsive to the seizure of the switch to institute the trunk hunting movement of the switch and wherein a switching relay operates to open the circuit of the line relay and to stop movement of the switch 20 and also prepare a holding circuit for itself, the initial operating circuit of the switching relay including contacts of the line relay 25 opened responsive to the release thereof, characterized by the fact that there is provided means for insuring a saturation of the line relay at the time its circuit is opened, thereby fixing the time taken for the line relay to 30 release regardless of whether the switch was or was not standing on an idle trunk when seized.

13. In a switch terminating a subscriber's line adapted to select an idle trunk when 35 used in an outgoing call and to disconnect the normal battery and ground connections when seized in an incoming call, a switching relay adapted to operate as a quick acting relay on incoming calls, and means for rendering said 40 relay slow to operate on outgoing calls.

14. In a trunk selecting switch, a line relay, a switching relay, two windings for said switching relay, means for operating the switching relay over one of said windings, 45 and means for rendering the switching relay slow to operate, said last means including the other of said windings and contacts of both said relays.

15. In a trunk selecting switch, a quick 50 acting relay, a slow acting relay, and means controlled jointly by said relays for rendering said first relay slow to operate under certain conditions.

16. In a trunk selecting switch including 55 a line relay and a switching relay, an operating winding for the switching relay, an auxiliary winding for the switching relay for rendering the relay slow to operate, and means for short circuiting said winding, 60 said means including contacts of the line relay and switching relay.

17. In a rotary line switch, a line relay operated responsive to an outgoing call, a switching relay operated in both outgoing 65 and incoming calls, an auxiliary winding for

the switching relay, and means including contacts of both of said relays for short-circuiting said auxiliary winding to render the switching relay slow to operate in outgoing calls.

18. In a rotary line switch, a line relay, a switching relay adapted to operate with the line relay either operated or unoperated, an auxiliary winding for the switching relay, and contacts on the line relay when operated for short-circuiting said auxiliary winding to render the switching relay slow to operate.

19. In a rotary line switch, a fast acting cut-off relay, means for operating said relay when the line is called, a line relay for controlling the switch to select an idle trunk when the line is calling, means for operating said cut-off relay to complete connection to a selected trunk, and means controlled by said line relay for rendering said cut-off relay slow to operate.

In witness whereof, I hereunto subscribe my name this 10th day of November, A. D. 1926.

HERBERT ADAMS.
